UNITED STATES PATENT OFFICE.

BENJAMIN F. HOWARD, OF INDIANAPOLIS, INDIANA, ASSIGNOR OF ONE-HALF TO
JOHN W. STAUB, OF INDIANAPOLIS, INDIANA.

LUBRICATOR.

1,026,867.

Specification of Letters Patent. Patented May 21, 1912.

Application filed June 5, 1911. Serial No. 631,326.

To all whom it may concern:

Be it known that I, BENJAMIN F. HOWARD, a citizen of the United States, residing at Indianapolis, in the county of Marion and State of Indiana, have invented certain new and useful Improvements in Lubricators, of which the following is a specification.

The object of this invention is to thoroughly nebulize lubricating oil and deliver it in that condition mixed with steam directly to the pipe which supplies steam to the cylinder of the engine.

I accomplish the object of the invention by the mechanism illustrated in the accompanying drawing which is an elevation and partial vertical section of a lubricator embodying my improvements.

Referring to the drawing, 1 is a main pipe through which steam for driving an engine is supplied to the steam chest in the usual manner (not shown).

2 is a branch pipe extending laterally from the main pipe 1. It discharges into a vertical pipe 3, preferably of less diameter, and the pipe 3 discharges into a conduit 4, extensions from which discharge into pipe 1 at a point nearer to the engine than that at which pipe 2 leaves it. As the return opening to pipe 1 is much smaller in area than the discharge into pipe 2, a pressure circuit is established by which properly nebulized lubricants added to the steam passing through said branch pipes will be injected into the head of steam in pipe 1 and carried through said pipe 1 to the steam chest and cylinder of the engine.

The lubricant, in the form of any of the usual cylinder oils, is contained in a reservoir 5 located above the conduit 4. This reservoir is filled full of oil at starting through an opening which is afterward closed by plug 6. The oil is fed out through pipe 7 which terminates with a nipple 8 the inner bore of which is tapered to form a seat for a needle valve 9 by which the discharge of the oil from the tank is regulated. As oil is forced from reservoir 5 by combined steam pressure and hydrostatic head produced by condensation forces the oil from the reservoir 5 through pipe 12, water is admitted through a pipe 10 to take its place. A condenser 11 is located above the reservoir 5 and pipe 10 takes from the lower end of the condenser and discharges near the

bottom of the reservoir. A pipe 12 connects the condenser with steam pipe 2 and steam coming through pipe 12 is cooled and condensed to water in said condenser ready for use as needed in the reservoir. A pipe 13 much smaller in cross-sectional area than pipes 3 and 4, takes steam from near the junction of the last two pipes and extending thence upwardly discharges it against the outer walls of the nipple 8, thereby heating the oil and blowing the drops of oil off of the end of the nipple and down into the surrounding tube 15 as they form. Steam pressure through pipe 13 also prevents the formation of a vacuum in tube 15 or an accumulation of oil or water in said tube or the occurrence of back pressure, any one of which might interfere with the operation of the device. Water of condensation forming in pipe 13 is returned by gravity through said pipe to the conduit 4 thereby preventing the gage glass 15 from becoming water-logged so as to interfere with the oil discharge through it. The oil is fed positively from reservoir 5 by the pressure of steam reaching it through pipe 12. The tube 15 will preferably be of glass through which the formation of drops may be seen and which will enable the supply to be regulated intelligently by a suitable opening or closing of the needle valve. Discharge from tube 15 is through channel 16 into conduit 4. The channel 16 curves from tube 15 downwardly and toward pipe 1 to cause the mixed oil and steam to be carried without obstruction by the steam flow in conduit 4. It will also be noted that the entrance to pipe 13 is in an upward curve which facilitates the supply of steam to said pipe.

Located in the conduit 4 is a nozzle 19 through which the oil, mixed with steam, is driven by the steam pressure through pipes 2, 3, and 4 and is thereby thoroughly nebulized. A gate valve 20 is located between the nozzle 19 and main pipe 1 and a globe valve 21 regulates the steam flow from pipe 2. The reservoir 5 is provided with glass tube 24 to show the height of water and oil in the reservoir and at the bottom of the tube is a cock 25 by opening which the tank may be drained of the accumulated water before refilling with oil.

The operation of my improved lubricator has been explained as its construction was described so that its operation will be

fully understood without further explanation.

Various modifications in proportion and arrangement of parts are possible without departing from the spirit of my invention, and I therefore do not limit myself to the exact construction here shown, but—

Having thus fully described my invention, what I claim as new and wish to set 10 cure by Letters Patent, is—

1. The combination with a main steam conducting pipe, of a branch pipe therefrom, an oil reservoir having a discharge nozzle, a condenser connected with the branch pipe 15 and discharging water of condensation into the oil reservoir to force the oil out, means connected with said branch pipe for supplying steam against said oil discharge nozzle and for returning water of condensation 20 to said branch pipe, means for nebulizing the oil and steam and means for discharging the product into said main pipe.
2. The combination with a main steam conducting pipe, of a branch pipe therefrom, which discharges through a reduced diameter into said main pipe at a point nearer the engine, an oil reservoir above 25 said pipe discharge, a steam condenser, means for supplying steam to the condenser, 30 means for connecting the condenser with the oil reservoir, a discharge from the reservoir terminating in a nipple, a needle valve seated in said nipple, means for discharging the oil issuing from the nipple into 35 said branch pipe, a steam conduit taking from the branch pipe below the nipple and discharging against the outer wall of the nipple, a nozzle in the branch pipe between its discharge end and said nipple, and means 40 to supply steam under pressure for forcing said oil product through the nozzle into said main pipe.

3. The combination with a main steam conducting pipe, of a branch pipe therefrom which discharges through a reduced diameter into said main pipe at a point nearer the engine, an oil reservoir, a steam condenser, means for supplying steam for the condenser 45 means for connecting the condenser with the oil reservoir, a discharge from the reservoir terminating in a nipple, a needle valve seated in said nipple, means for discharging the oil issuing from the nipple into said branch pipe, a steam conduit taking from the branch pipe considerably below the 50 nipple and discharging against the outer wall of the nipple, a nozzle in the branch pipe between the nipple and the main pipe, and a steam pipe from said branch pipe between the nipple and branch pipe inlet to 55 supply steam pressure for forcing the oil product from the nipple through the nozzle.

4. The combination with a main steam conducting pipe, of a branch pipe therefrom discharging into said main pipe at a point nearer the engine, an oil reservoir above 60 said discharge of the branch pipe, a steam supply pipe thereto, a discharge pipe therefrom to the branch pipe, a nipple in said last pipe, a nozzle in the branch pipe between its discharge into the main pipe and the discharge of the reservoir pipe into it, and a pipe taking steam below the oil reservoir from the branch pipe and discharging 65 into the upper end of said reservoir 70 discharge pipe against the nipple.

In witness whereof, I, have hereunto set my hand and seal at Indianapolis, Indiana, this 26th day of May, A. D. one thousand nine hundred and eleven.

BENJAMIN F. HOWARD. [L. S.]
